UNITED STATES PATENT OFFICE

93,151

DESIGN FOR A RETURN-BALL BAT

Guy M. Young, Los Angeles, Calif.

Application November 21, 1933, Serial No. 49,808

Term of patent 7 years

To all whom it may concern:

Be it known that I, GUY M. YOUNG, a citizen of the United States, and residing at Los Angeles, in the county of Los Angeles and State of California, have invented a new, original, and ornamental Design for Return-Ball Bat, of which the following is a specification, reference being had to the accompanying drawing forming part thereof, in which:

Figures 1 and 2 are, respectively, views in front and in rear elevation of a return-ball bat showing my new design.

I claim:

The ornamental design for a return-ball bat as shown.

GUY M. YOUNG.
